SHOE SEWING MACHINE

Otto R. Haas, North Beverly, Mass., assignor to
United Shoe Machinery Corporation, Borough
of Flemington, N. J., a corporation of New Jersey

Original application April 29, 1936, Serial No.
76,924. Divided and this application April 6,
1938, Serial No. 200,413

4 Claims. (Cl. 112—59)

The present invention relates to sewing machines, and more particularly to improvements in thread tensioning mechanism therefor. The illustrative embodiment of the invention is similar 5 to that disclosed in inventor's pending application Serial No. 76,924, the present application being a division of said case.

There is frequently employed in sewing machines, particularly those of the lockstitch type, 10 auxiliary thread tensioning mechanism adapted to act upon the thread between the take-up and the looper to aid in the performance of the looping operation. Such supplementary tensioning devices are, however, subject to the disadvantage 15 that the operation of re-threading the machine is rendered more difficult and the time required for such operation therefore increased.

As a general rule, the thread handling mechanisms of sewing machines are enclosed, not only 20 to protect the operator from injury but also, in the case of wax thread sewing machines, to provide a heat-retaining enclosure for the thread in its passage from the wax pot through the take-up and auxiliary tensioning devices to the looper.

In order to provide access to the enclosed devices to permit re-threading of a new thread supply, and for purposes of repair or adjustment of the parts, removable covers are employed. It has been found that the operator, upon completion 30 of the threading operation or the like, is apt to fail to close or replace the cover, with the result that the machine is then operated with the thread under improper temperature conditions and with increased risk of injury to the operator from the 35 unprotected parts.

With the above consideration in mind it is, therefore, an object of the present invention to provide novel and improved thread tensioning mechanism for sewing machines, said mechanism 40 being so constructed and arranged as to simplify substantially the operation of re-threading the machine.

Another object of the invention is the provision in a sewing machine of thread handling mechanism of such construction and arrangement that the operator will of necessity keep the cover for the thread handling devices closed while the machine is running.

With these objects in view, a feature of the 50 present invention consists in the provision in a sewing machine having stitch forming and thread handling devices and a pivotally mounted cover for certain of said devices, of thread tensioning mechanism accessible for insertion of the thread 55 therein when the cover is opened, and operative

to tension the thread only when the cover is closed.

More specifically, a feature of the invention consists in the provision in a sewing machine having stitch forming and thread handling devices including a thread take-up, of a cover for enclosing certain of the devices, said cover being pivotally mounted to permit access to the same, and a frictional tension device acting with a yielding pressure on the thread between the 10 take-up and the sewing point and comprising members having thread engaging surfaces, one of the members being carried by the cover, whereby the device may be readily threaded when the cover is open and the device rendered operative 15 to tension the thread only upon closing the cover.

In the drawings illustrating the preferred embodiment of the invention, Figure 1 is a view in front elevation of the head portion of a shoe sewing machine embodying the invention, showing the cover for the take-up mechanism in closed position, which mechanism is indicated in dotted line; Figure 2 is a view in side elevation, partly in section, of the machine adjacent the sewing point and showing a portion of the auxiliary 20 thread tensioning mechanism, the covers for the tension wheel and take-up mechanism being largely broken away; and Figure 3 is a detail plan view, partly in section, of the auxiliary thread 25 tension device.

The machine illustrated in the drawings is an outsole lockstitch shoe sewing machine more fully illustrated and described in inventor's application Ser. No. 76,924 above referred to, only so much of the machine being illustrated in the 35 drawings as is necessary to a full understanding of the invention. The work support of the machine is indicated at 4, and the presser foot at 6, while the stitch forming and thread handling devices adjacent the sewing point include a 40 curved hook needle 8, a curved awl 10, a needle threading looper 12 and thread finger 14. A rotary loop taker is mounted above the sewing point in a circular guideway 16 in the machine frame 18, and the locking thread case in turn is 45 supported in a guideway in the loop taker. The various devices are actuated by connections from a sewing cam shaft 20 in the head of the machine.

The machine is provided with a take-up 22 by which the loop of the needle thread, after 50 being carried over the locking thread case by the loop taker, is drawn into the work to set the stitch. The take-up 22 is secured to one end of a shaft 24 rotatably mounted in the front portion of the machine frame below the sewing point. 55

The shaft is rocked by connections from the cam shaft 20 to oscillate the take-up arm close to a stationary side flange portion 26 extending forwardly from the machine frame and provided at 5 its forward edge with a sidewardly directed rim portion 27.

Each stitch is set against a uniform tension in the needle thread, this tension being provided by a tension wheel 28 rotatable in the main 10 frame of the machine. The tension wheel is normally entirely enclosed by a hinged cover 30, and is provided with a brake 32, the adjustment of which is effected by a thumb nut 34. From the tension wheel the needle thread passes over an 15 idler pulley 36 and about an auxiliary take-up 30, thence over idler pulleys 39 and 40 to the pulley 42 on the main take-up lever 22. The thread, prior to passing over the tension wheel 28, is drawn through the usual wax pot, not shown.

20 To retain the thread in properly heated condition in its passage over the auxiliary and main take-ups 38 and 22 respectively, and to shield the operator from the rapidly oscillating take-up lever, there is provided a cover 44 having a forwardly offset portion 45 generally parallel to and adapted to cooperate with the rim portion 27 of the projecting flange 26 to form an enclosure for the take-up mechanism. The cover is mounted on the machine frame by means of a horizontal 30 hinge 46 at its lower edge to permit the cover to be swung outwardly and downwardly away from the take-up 22 to render the needle handling devices accessible for re-threading and for repair and adjustment. A handle 48 on the cover enables the same to be opened and closed conveniently.

To assist in carrying out the looping operation by insuring that the needle thread will be stretched between the looper 14 and the thread finger 16 so as to engage and be retained in the needle hook, there is provided an auxiliary frictional tension device acting upon the needle thread between the take-up 22 and the looper 14. In order that the re-threading operation may not 45 be rendered more difficult by the addition of the said auxiliary tensioning device the mechanism therecif is mounted partly on the take-up cover 44 and partly on the flange portion 26 of the casing so that the device is opened automatically when the take-up cover is opened.

50 The thread tensioning mechanism comprises a plate 50 slidably mounted in the upper part of the flange 26 of the take-up casing, the plate being so positioned relative to the lead of the thread between the pulley 42 on the take-up lever 22 and the looper 12 that the thread is drawn to the sewing point across the face of the plate, as shown in Figure 2. A headed pin 52 (see Figure 3), secured at one end to the plate 50 and passing loosely through the side of the flange serves to hold the plate in position while permitting movement of the plate laterally. The plate is urged away from the flange and toward the portion 45 of the cover 44 by small springs 55 received in recesses in the flange 26.

70 The forwardly offset portion 45 of the take-up cover 44 is formed along its upper edge with a suitable surface 56 substantially parallel to and arranged to cooperate with the plate 50 of the tension device. When the cover 44 is swung open to expose the take-up mechanism, the surface 56 is moved forwardly out of alignment with the plate 50 and the thread between the take-up lever 22 and the looper 12 passes loosely across

the surface of the plate 50, as in Figure 2. When the cover is swung into the closed position shown in Figure 3, a bevelled surface 58 on the cover forces the thread to the right, the plate 50 yielding to permit the thread to enter between the 5 parallel friction surfaces of the cover and plate.

By this arrangement of take-up cover and thread tensioning mechanism, not only is the operation of re-threading the machine substantially simplified, but also it is insured that the operator will close the cover before starting the machine, since the thread tension necessary to the proper operation of the machine is obtained only with the cover in closed position.

10 While the invention has been illustrated and described as embodied in a lockstitch shoe sewing machine of particular construction and arrangement, the invention is not limited thereto in its application, and may be embodied in sewing machines of other types. Nor is the invention limited to the particular form and arrangement shown and described, but embraces other constructions and arrangements within the scope of the appended claims.

20 Having thus described the invention, what is claimed is:

1. A sewing machine having, in combination, 30 stitch forming and thread handling devices, a cover for enclosing certain of said devices, the cover being movable away from closed position to permit access to the devices, and frictional thread tension mechanism comprising members having thread engaging surfaces arranged to act with yielding pressure on the thread between certain of the thread handling devices when the 35 cover is in closed position, movement of the cover away from closed position causing the thread engaging surfaces to separate to permit insertion of the thread therebetween.

2. A sewing machine having, in combination, 40 stitch forming devices comprising a hook needle and a take-up, a pivotally mounted cover to enclose or permit easy access to certain of the stitch forming devices, and a frictional tension device 45 acting with a yielding pressure on the thread between the take-up and the point of operation of the needle and comprising members having thread engaging surfaces, one of which is carried by said cover.

3. A sewing machine having, in combination, 50 stitch forming devices comprising a hook needle and a take-up, a shaft on which the take-up is mounted, a removable cover for the take-up, and a frictional tension device acting with a yielding pressure on the thread between the take-up and the point of operation of the needle, and comprising members having parallel thread engaging surfaces disposed at right angles to the take-up shaft, one of said surfaces being carried by said cover.

4. A sewing machine having, in combination, 55 stitch forming devices comprising a hook needle and a take-up, a shaft on which the take-up is mounted, a stationary guard at one side of the path of movement of the take-up, a removable cover arranged when in position to surround the other side of the take-up path, and a frictional tension device acting with a yielding pressure on the thread between the take-up and the point of operation of the needle and comprising members having thread engaging surfaces, carried by 65 said guard and said cover, respectively.
